UNITED STATES PATENT OFFICE.

ADAM W. KAUFMAN, OF MILWAUKEE, WISCONSIN, ASSIGNOR TO RES MANUFACTURING COMPANY, OF MILWAUKEE, WISCONSIN.

DETACHABLE ROLLER.

1,023,939.

Specification of Letters Patent.

Patented Apr. 23, 1912.

Application filed May 6, 1911. Serial No. 625,419.

To all whom it may concern:

Be it known that I, ADAM W. KAUFMAN, a citizen of the United States, and resident of Milwaukee, in the county of Milwaukee and State of Wisconsin, have invented certain new and useful Improvements in Detachable Rollers; and I do hereby declare that the following is a full, clear, and exact description thereof.

10 My invention has for its object to provide a simple and effective roller especially designed to be applied to toilet-paper holders, its arrangement and construction being such that the roller, when inserted within a roll 15 of toilet-paper and thereafter adjusted to a holder, will automatically lock, whereby the roller and paper-roll contained therein cannot be removed until the roll is exhausted, thus rendering theft of the paper in its 20 entirety impossible.

While the primary object of the invention is as stated above, it should be understood that the roller may also be utilized for towel racks or the like in instances where a quick 25 detachable roller is required.

With the above objects in view, the invention consists in certain peculiarities of construction and combination of parts to be hereinafter set forth with reference to the 30 accompanying drawings and subsequently claimed.

In the drawings Figure 1 represents a plan view partly broken away of a holder equipped with a spindle embodying the features of my invention; Fig. 2, an elevation of the same with parts broken away and parts in section to better illustrate the invention.

Referring by numerals to the drawings, 1 40 indicates a bracket provided with rigid arms 2, 2^a, having bearing apertures 3, 3^a, adapted to receive separable members 4, 5, of a detachable spindle. The spindle-member 5 comprises a hollow shell, which is revolvably 45 mounted in aperture 3 of the bracket-arm 2, a head 6 of the spindle-member 5 being adapted to abut the outer face of said bracket-arm adjacent to its aperture. The 50 opposite end of the spindle-member 5 is fitted into a countersunk annular groove 7, that is disposed about the inner edge of the bearing aperture 3^a, of bracket-arm 2^a. Fitted through the aperture 3^a of this arm is a plug 8, which plug, together with a head 9 55 that extends therefrom, constitutes the oppo-

site detachable spindle-member, the head 9 being adapted to engage the face of the bracket-arm 2^a. The plug 8 extends into the spindle-member 5, terminating with a conical head 8^a, which head serves as a guide to 60 facilitate insertion of this member within the spindle-member 5. The plug 8 is also provided with a flattened face that serves as a seat for a flat spring 10, which spring is secured to said plug. The free end of the 65 spring is provided with a lug 11 that is adapted to engage an aperture 12 in the spindle-member 7, and when engaged, the lug thus locks the two members together.

In assembling the parts, a roll of paper is 70 inserted upon the outer spindle-member 5 as the same is pushed through the aperture 3^a of the bracket-arm, the end of the spindle being adapted to socket within the annular recess 7 of bracket-arm 2^a, which recess 75 forms a support for this end of said spindle. The locking-member 4 is then inserted through the aperture 3^a of bracket-arm 2^a, being forced inwardly until the face of its head 9 abuts the adjacent face of said 80 bracket-arm 2^a, and in this position the lug 11 of the flat spring carried by said member is aligned with the aperture in the spindle-member. The spindle-member is then rotated until the lug 11 will engage the aperture, which it enters due to pressure exerted 85 by the spring. The spindle as a whole is then locked within the bracket and cannot be detached until the roll of toilet-paper has been practically exhausted, whereby access 90 may be had to the lug 11, which can then be depressed by the finger or any accessible tool and the parts can then be separably removed 95 from the bracket for the purpose of renewing the toilet-paper roll.

I claim:

A holder comprising apertured bracket arms, one of which apertures is provided with a counter sunk annular groove, a centrally apertured hollow shell fitted into the 100 arm apertures, the shell being provided at one end with a head that abuts one of the bracket arms, the opposite end being open and fitted into the annular counter sunk groove of the opposite bracket arm, a plug 105 fitted through the annular groove apertures of aforesaid bracket arm, the plug being extended into the open end of the shell and provided with a head that engages said last mentioned annular grooved bracket arm, a 110

flat spring secured to said plug and a lug carried by the spring engageable with the shell aperture, whereby the same is locked within the bracket that constitutes fixed bearings for the shell.

In testimony that I claim the foregoing I have hereunto set my hand at Milwaukee in

the county of Milwaukee and State of Wisconsin in the presence of two witnesses.

ADAM W. KAUFMAN.
